DESIGN FOR AN INCENSE BURNER OR ANALOGOUS ARTICLE

Clarence William Parker, Lynn, Mass.

Application March 14, 1941, Serial No. 99,598

Term of patent 7 years

To all whom it may concern:

Be it known that I, Clarence W. Parker, a citizen of the United States, residing at Lynn, in the county of Essex and State of Massachusetts, have invented a new, original, and ornamental Design for an Incense Burner or Analogous Article, of which the following is a specification, reference being had to the accompanying drawing, forming part thereof.

Figure 1 is a perspective view of an incense burner or analogous article showing my new design.

Figure 2 is a side elevational view thereof.

I claim:

The ornamental design for an incense burner or analogous article, as shown.

CLARENCE WILLIAM PARKER.
